UNITED STATES PATENT OFFICE.

LEO BETHKE, OF MILWAUKEE, WISCONSIN, AND HERBERT C. FOLLINGER, OF CHICAGO, ILLINOIS.

CAN OPENER.

Application filed December 22, 1920. Serial No. 432,409.

To all whom it may concern:

Be it known that we, LEO BETHKE and HERBERT C. FOLLINGER, citizens of the United States, and residents of Milwaukee and Chicago, in the counties of Milwaukee and Cook, and States of Wisconsin and Illinois, respectively, have invented certain new and useful Improvements in Can Openers, of which the following is a full, clear, and exact specification.

Our invention is concerned with can openers, and is designed to produce a device of the class described that will cut out a disk or other shaped section from the top of the can and lift it out without forcing it down into the can at all and thus disarranging the contents of the can.

It is further concerned with a device of the class described that can be driven by a motor and operated rapidly so as to have a large capacity with no other manual labor than that involved in seating the can on the apparatus and then withdrawing it.

To illustrate our invention, we annex hereto a sheet of drawings in which the same reference characters are used to designate identical parts in all the figures, of which—

Fig. 1 is a side elevation of our can opener; and

Fig. 2 is a section on the line 2—2 of Fig. 1 with the can removed, and

Fig. 3 is an enlarged portion of Fig. 1 but with the angle of the non-cutting edge of the tooth exaggerated.

The basis of our invention is a novel cutting blade α , which for round cans will be curved into a circle and provided with a plurality of teeth β , preferably four, each of which has a single cutting edge c suitably sharpened, the other edge d being dull, and while it might be vertical, we preferably incline it a little, as shown, so that the heel of one cutting edge slightly overlaps the point of the adjacent one. With the construction described, when the blade is forced down on the top of the can, it punctures it at a plurality of equidistant points, and a cut then runs from each point in one direction only to the adjacent point, with the result that there is at no time, until the cut is completed, any possibility of any part of the cut out portion being bent down by the friction of the blade, as would be possible if the teeth were equilateral and had two cutting edges.

With our novel construction, the disk is cut

out substantially flat and adheres to the inner sides of the teeth so that it is lifted out by them when the blade is retracted, a result not heretofore attained by any can opener with which we are familiar.

By reason of the edges d being inclined, as shown, so that the heel of each cutting edge c overlaps the point of the adjacent cutting edge c , we virtually insure the registration of the cut made by the heel of each edge c , so that when the blades are forced down so that the heels of the edges pass through the tin, then the cut is completed without any possible breaks through the entire 360 degrees.

While we might simply secure the blade to a handle, as in the Snow and Coe Patent No. 233,813, we preferably mount it in a frame e , which may be provided with the screws f to secure it to a wall, and which has a vertical bearing g for the plunger h carrying the head j , to the under side of which the blade α is secured in any desired manner. A supporting flange k carried by the frame has a pair of positioning lugs l on its upper surface to center the particular can for which it is designed readily beneath the blade α . While we might provide a handle or lever for reciprocating the plunger h manually, we preferably secure to the frame a small electric motor m , and provide its armature shaft or an extension of it with a worm n meshing with a worm wheel o journaled on a bearing p preferably located in a housing q for the gearing, and on the wheel o we locate an eccentric pin r , which is conveniently connected with the top of the plunger by the link s pivoted thereto. To knock the cut-out part of the top automatically out of the blade as it rises, we extend a protection t from the frame down through an opening u in the head j .

The lugs l are undercut, and in the front of the flange k we form a slot v through which extends the hook w secured to the rod x sliding in the bearings y formed on the under side of the flange k . A helically coiled expanding spring z is interposed between one of the bearing lugs y and the hook w so that the bottom of the can may be easily caught under the lugs l and the hook w and held down thereby when the knife ascends and tends to carry the can with it.

While we have shown and described our invention as embodied in the form which at

present we consider best adapted to carry out its purposes, it will be understood that it is capable of some modifications, and we do not desire to be limited in the interpretation of the claims except as may be necessitated by the state of the prior art.

We are aware of the structures of the Snow and Coe patent above referred to, and those of the patents to Johnson No. 1,116,592, dated November 10, 1914, and Mendenhall No. 1,182,781, dated May 9, 1916, and do not claim the same as our invention, but what we do claim, and desire to secure by Letters Patent of the United States is:

15 1. In a can opener, a holder and a blade member secured therein having a plurality of teeth, each of said teeth having only one cutting edge, and all of them combined completely circumscribing 360° by said cutting edges, the non-cutting edges of the teeth being inclined to the line of movement so that the heel of one cutting edge slightly overlaps the point of the adjacent one, and means associated with said holder and blade member so as automatically to knock out the portion of the can cut out and lifted by the blade.

20 2. In a can opener, the combination with a frame, of a can support associated therewith, a plunger mounted to reciprocate in

the frame above the support, a blade member carried by the plunger having a plurality of teeth which combined circumscribe 360 degrees by their cutting edges, means acting automatically as the plunger rises to 35 knock out the portion of the can cut out and lifted by the blade, a shaft supported by the frame, reducing gearing from the shaft to the plunger to transform the rapid rotation of the shaft to a comparatively slow reciprocation of the plunger, and means to rotate the shaft.

3. In a can opener, the combination with a frame, of a can support associated therewith, a plunger mounted to reciprocate in 45 the frame above the support, a blade member carried by the plunger having a plurality of teeth, a drive shaft supported by the frame, a worm carried by said drive shaft, a worm gear wheel journaled on the frame, an eccentric pin carried by the worm gear wheel, a connection from the eccentric pin to the plunger, and means to rotate the vertical shaft.

In witness whereof, we have hereunto set 55 our hands and affixed our seals this 30th day of November, A. D. 1920.

HERBERT C. FOLLINGER. [L.S.]
LEO BETHKE. [L.S.]
